UNITED STATES PATENT OFFICE.

MURL E. FULK, OF UNION FURNACE, OHIO.

RADIATOR PROTECTOR.

Application filed October 18, 1922. Serial No. 595,327.

To all whom it may concern:

Be it known that I, MURL E. FULK, a citizen of the United States, residing at Union Furnace, in the county of Hocking and State of Ohio, have invented new and useful Improvements in Radiator Protectors, of which the following is a specification.

This invention contemplates the provision of a radiator protector and mud shield for motor operated vehicles, and provides a device of this character which can be quickly attached to or removed from the radiator, and when in use, prevents mud from 15 clogging the radiator, and also serves in the capacity of a bumper to prevent injury to the radiator.

Another object of the invention resides in associating with the protector, a plurality 20 of shutters which can be conveniently manipulated from the instrument board of the vehicle, and utilized to assist the protector from preventing mud finding its way between the fins and tubes of the radiator, as 25 well as being useful as an antifreeze device for the radiator.

The nature and advantages of the invention will be better understood when the following detailed description is read in 30 connection with the accompanying drawings, the invention residing in the construction, combination, and arrangement of parts as claimed.

In the drawings forming part of this application, like numerals of reference indicate similar parts in the several views, and wherein:

Figure 1 is a front elevation of the device showing it associated with a radiator.

Figure 2 is a sectional view taken on line 2-2 of Figure 1.

Figure 3 is a fragmentary top plan view.

Fig. 4 is a fragmentary perspective view of the protector and shield.

Figure 5 is a front elevation partly in section showing a modified form of the invention.

Figure 6 is a sectional view therethrough showing the device associated with the radiator.

The device forming the subject matter of the present invention embodies a frame 10 which may be constructed from any suitable material and vary in size and configuration 55 to accommodate itself to different designs of automobile radiators. The frame 10 sup-

ports a sheet of galvanized screening indicated at 11, of the proper mesh to prevent mud from finding the way to the radiator proper with its usual detrimental effects, 60 and at the same time allows proper aeration. The frame 10 includes a vertically disposed reinforcing element or strip 12, and is shaped to embrace the radiator as illustrated. The upper end of the frame supports a two-part clamp which overlies the hood and is designed to embrace the filling tube of the radiator, the two part clamp being indicated at 14, the lower end of the frame is provided with extensions 15 which 70 are adapted to be associated with any appropriate part of the vehicle with which the protector is used, and when used in connection with Ford automobiles, are secured to the spring clip bolts 16.

The frame 10 also supports lugs 17 arranged to hold the frame slightly spaced from the radiator proper to allow proper aeration.

In Figures 5 and 6, I have illustrated a 80 modified form of the invention wherein the frame of the protector is indicated at 10' and supports a sheet of galvanized screening indicated at 11'. This frame in its entirety is identical in construction with the frame 85 illustrated in Figure 4, and mounted on the radiator in the same manner as herein above described in connection with the preferred form of the invention.

However it will be noted in Figures 4 and 90 5 that I make use of a plurality of shutters indicated at 18 which are arranged within the frame 10' and pivoted between the parallel side members thereof. These shutters occupy approximately one-third of the space 95 at the lower end of the frame, and are connected by a rod 19 which operates to open and close all of the shutters simultaneously. The rod 19 is terminally connected with the adjacent branch of a bell crank lever 20, 100 pivoted as at 21, the remaining branch of this lever being connected with a manipulating rod 21'. The rod is arranged horizontally, passing through an opening in the instrument board of the vehicle not shown, 105 and in convenient reach of the driver. The shutters are just wide enough to snugly fit between the parallel sides of the frame 10' when open, and when these shutters are closed the adjacent edges thereof overlap 110 to form a close wall that will exclude cold air, and thus serve in the capacity of an

antifreezing device for the radiator. In addition to this fact, the shutters when closed prevent foreign matter which would otherwise pass through screening 11 from finding its way between the fins and tubes of the radiator.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

15 What I claim is:

1. A combined protector and mud shield for automobile radiators, comprising a frame designed to embrace the radiator, a sheet of screening material supported by the frame directly in advance of the radiator,

means arranged at the top and bottom of said frame and associating the latter with the radiator, and lugs carried by the frame and arranged to contact the radiator to space the frame therefrom for proper aeration.

2. An automobile radiator attachment of the character described comprising a frame adapted to embrace the radiator, a sheet of screening material supported by the frame directly in advance of the radiator, means for supporting the frame upon the radiator, a plurality of shutters pivoted within the frame adjacent the lower end thereof, and means whereby said shutters may be simultaneously opened or closed.

In testimony whereof I affix my signature.

MURK E. FULK.
